The ornamental design for a side rib for a planer, as shown and described.

DESCRIPTION

FIG. 1 is a left side perspective view from the front of a first embodiment of a side rib for a planer showing my new design:

FIG. 2 is a top plan view of the first embodiment;
FIG. 3 is a back elevational view of the first embodiment;
FIG. 4 is a front elevational view of the first embodiment;
FIG. 5 is a right side elevational view of the first embodiment;

FIG. 6 is a left side elevational view of the first embodiment; FIG. 7 is a left side perspective view from the front of the first embodiment, shown in an alternate condition of use; and

FIG. 8 is a left side perspective view from the front of a second embodiment of a planer showing my new design with an installed knob.
